SEWING MACHINE

Joseph Schifter, New York, N. Y., assignor, by
mesne assignments, to Columbia Blindstitch
Machine Co., Inc., New York, N. Y., a corpora-
tion of New York

Application February 2, 1940, Serial No. 316,892

18 Claims. (Cl. 112—198)

This invention relates to sewing machines. It is an object of the invention to use a substantially conventional sewing machine head, with very little change in the operating mechanism, for making an imitation hand stitch, a stitch which may hereinafter be termed a "saddle stitch."

It is an object of the invention to provide mechanism for making a saddle stitch in which the stitch formation is effected by simple, conveniently accessible, and easily adjustable parts, and where such parts are capable of incorporation into sewing machines now being produced, with but minor changes in such sewing machines.

It is an object of the invention to provide apparatus for producing, by a machine involving a minimum number of parts, simply assembled and easily adjustable, a stitch closely imitating hand stitching.

Other objects of this invention will be set forth hereinafter, or will be apparent from the description and the drawings in which are illustrated embodiments of apparatus exemplifying the invention.

The invention, however, is not intended to be restricted to any particular construction, or any particular arrangement of parts, or any particular application of any such construction or arrangement of parts, or any specific method of operation, or any of various details thereof, herein shown and described, as the same may be modified in various particulars or be applied in many varied relations without departing from the spirit and scope of the claimed invention, of which the exemplifying embodiments, herein shown and described, are intended only to be illustrative, but not to show all the various forms and modifications in which the invention might be embodied.

On the drawings, in which the same reference characters refer to the same parts throughout, and in which the exemplifying embodiments appear:

Fig. 1 is an elevational view of a machine embodying certain features of the invention, parts being shown in dotted lines and broken away;

Fig. 2 is a bottom plan view of the machine shown in Fig. 1, to slightly smaller scale;

Fig. 3 is an end elevational view, to an enlarged scale, of the needles and stitch-forming mechanism of the machine shown in Fig. 1, associated parts of the stitch-forming mechanism being shown in dot-and-dash lines, and other parts being broken away in cross-section for the purposes of clarity;

Fig. 4 is a detail elevational view, illustrating

the association of a part of the stitch-forming mechanism, parts being shown broken away in cross-section, substantially as seen from the line 4—4, of Fig. 3;

Fig. 5 is a detail plan view of a part of the stitch-forming mechanism shown in Fig. 3;

Fig. 6 is a detail elevational view, parts being shown in cross-section, illustrating a stage of the stitch-forming operation in which the needles

10 have been extended through the fabric;

Fig. 7 is a view, similar to Fig. 6, showing a portion of a subsequent stage of the stitch-forming operation in which the thread has been distended by the hook from the thread-carrying

15 needle past the hook needle;

Fig. 8 is a view, similar to Figs. 6 and 7, showing the complete subsequent stage of the stitch-forming operation in which the finger has come into action to press the distended loop against the

20 hook needle;

Fig. 9 is a plan view, the hook being shown in section, illustrating the functioning of the parts in their relationship shown in Fig. 8;

Fig. 10 is a perspective view, partly in cross-section, illustrating the stitch produced by apparatus such as shown in the drawings;

Fig. 11 is a view, similar in part to Fig. 3, but showing a modified construction of the operating elements of the stitch-forming mechanism, the 30 presser foot and details of the feeding mechanism not being shown; and

Fig. 12 is a side elevational view of the mechanism shown in Fig. 11.

The invention will be illustrated in the form 35 it may take when applied to a well-known and conventional sewing machine 10. Such a sewing machine may include a base 12 having the usual hollow upright bracket 14 extending upwardly therefrom, the hollow arm 16 extending, in sub-

40 stantially the usual manner, over base 12 to present the usual front bearing upright 18 immediately over needle plate 20 provided in base 12. Upright 18 may provide bores or other suitable guides in which may slide presser foot bar 22

45 and needle bar 24. In arm 16 may be positioned a shaft 26 (shown dotted, and only in part) from which, by suitable mechanism (not shown), reciprocating motion is imparted to needle bar 24. A combined pulley-and-hand wheel 28 is attached

50 to the shaft at the end thereof extending beyond arm 16, and provides for association therewith of a belt or other suitable means for driving the machine.

Needle bar 24, at its lower end, is provided 55 with a chuck 30 for receiving a pair of needles.

These needles are thread-carrying needle 32 and hook needle 34. Thread-carrying needle 32 receives a single thread 36 from any suitable spool or other source of supply through the necessary tensions and feed pick-ups, which need not be specifically designated here. Both needles are reciprocated by the needle bar to pass through an opening 38 in presser foot 40 and openings 42 in the needle plate to penetrate fabric 44 which may have been positioned upon the needle plate. The presser foot, carried by bar 22, cooperates with feed dogs 46 (all but the teeth of which are shown by dot-and-dash lines in Fig. 3), positioned beneath the base and operable to move in, and be projected through, slots 48 in needle plate 20 provided for that purpose. Of course, the presser foot may be lifted free of the needle plate, in the usual manner, by suitable means which engage the presser foot bar for the purpose; but, normally, when such means are released, resilient means drive the presser foot against the needle plate or such fabric as may be positioned on the needle plate.

The usual feed action for feed dogs 46 may be obtained from eccentrics, operating from shaft 26 through eccentric straps 50 and 52 (shown only in part, and dotted in Fig. 1) to actuate bell cranks 54 and 56. Bell crank 54, in turn, may oscillate a link 58 to which feed dogs 46 may be fastened, the motion derived from link 58 being that necessary for motion of the feed dogs in the direction of feed, as, for instance, in the direction of the arrow in Fig. 3. Bell crank 56, by engagement of a roller 60 carried on the end of one of its arms 62 in a yoke 64 on link 58, effects lifting and lowering of feed dogs 46 into and out of engagement with the fabric and the presser foot.

Suitably mounted on the under side of base 12, as, for instance, in bearing lugs 63 and 65 is a shaft 66. Lug 65 may be one of the feet 68 on which the base, and, therefore, the machine, may be rested. Suitable means may be provided for rotating shaft 66 from shaft 26. In the instance shown, bevel gears 70 provide engagement between shaft 66 and a vertical shaft 72, the vertical shaft being driven from shaft 26 in any desired manner. In the instance shown in Fig. 1, the gear ratio is such that shaft 66 is driven twice as fast as shaft 26.

Shaft 66, at bearing lug 65, may have a pin section 74 secured thereon, section 74 being of larger cross-section than shaft 66 and being provided a bearing in lug 65. A pin 76 extends laterally from end face 78 of section 74, and is disposed eccentrically relatively to the center of shaft 66. In the instance shown, the pin, integral with section 74, extends into a slot 80 in an arm 82, so that a roller 83 on the end of the pin engages the walls of the slot. The arm is part of a unitary member 84 having a bearing section 86 into a bore 88 of which a stud 90, fixed in bearing lug 65, extends. Slot 80 is disposed in arm 82 so that, as shaft 66 rotates, roller 83 of pin 76 will slide in slot 80 and oscillate the arm. Thus slot 80 may be angularly disposed in arm 82, the degree of angularity being one of the factors in determining the amplitude of oscillation of arm 82. By changing the angularity, or the position or shaping, or any one or more of them, of the slot, a different amplitude or character of oscillation may be imparted to arm 82. The motion of pin 76 within slot 80, in oscillating arm 82 about stud 90 as a center, imparts such movement to a plate 92, which is

affixed to arm 82 at its upper end, and has a tooth 94 formed thereon, so that this tooth moves relatively to the needles in the manner to be described.

Member 84 also includes a rocker arm 96 which may be formed substantially integrally with bearing section 86 from which arm 82 extends substantially oppositely to arm 96. Extending from the lower end of rocker arm 96 is a pin 98 which may provide means for associating a ball-and-socket connection 100 between the pin and a link 102. The link has openings at its opposed ends, and with each one of these openings is associated a ball-and-socket connection. The two connections are here shown turned so as to be disposed in planes at 90° to each other. The ball-and-socket connection 104 opposed to connection 100 is also associated with a pin 106 which is substantially integral with an arm 108. Arm 108 is affixed to a spindle 110, which is provided a bearing in a sleeve 112. The sleeve is shown as fixed in a bracket 114 which, in turn, is secured to and extends downwardly from the bottom face of the base.

The spindle extends through the sleeve and the bracket to a position above the bracket, at which position an arm 116 is affixed to the spindle. Arm 116 is thus positioned between tooth 94, even at the uppermost portion of the travel of the tooth, and needle plate 20. Arm 116 has an arcuately shaped pusher or plunger finger 118, the center of the arc being substantially in spindle 110. The end of the finger is formed with a point 120 and a vertical edge 122. The position of the arc is such that, on oscillation of the finger, point 120 and edge 122 will be moved between the needles when the needles extend through the needle plate and fabric on the needle plate, as shown in Figs. 8 and 9.

The needles are shown lined up in the direction of feed of fabric as effected by dogs 46 in the direction indicated by the arrow in Fig. 3. The direction of oscillation of arm 82, and, therefore, of tooth 94, is parallel to the direction of feed effected by cooperation of dogs 46 and presser foot 40. The tooth itself, as shown in Figs. 5 and 6, as arm 86 is oscillated, is presented immediately beside eye 124 of needle 32. When needle 32 carries thread 36 engaged in eye 124 through fabric 44, and then is started on retraction, the slack thus produced in the thread forms a loop 126. Tooth 94 is so presented that it will engage within loop 126 thus formed. The tooth, engaging the loop and continuing its oscillation, is effective to draw the thread from needle 32 towards and then past needle 34 and its hook 128, as shown in Fig. 7.

At this stage of the operation, as shown in Figs. 8 and 9, finger 118 moves between the needles above tooth 94 and into engagement with the line 130 of thread forming loop 126 as drawn by the hook. The vertical edge 122 engages the line 130, which is prevented from sliding off by point 120, and this line is pressed by finger 118 against needle 34, as shown in Fig. 9, so that hook 128, on retraction of the needles, will draw the loop through the fabric to the outer side, where the transfer of thread and further interlock with the thread carried by needle 32, follows in producing the chain stitch. The engagement of finger 118 and line 130 takes place between tooth 94 and the fabric. Excessive breaking stress upon the thread is thus avoided, as the elasticity of the fabric contributes to facility in stretching the loop onto hook 128.

By proper feed adjustment, that is, by adjustment of the eccentricities and link motions entering into the travel of the feed dogs, the laying down of thread on the outside of the fabric is such that thread will be apparent only at intervals on the outside of the fabric. In order to produce saddle stitching, that is, imitation hand stitching, at the outside face of fabric, the feed must be such that the fabric, after the needles are withdrawn, will be moved sufficiently so that needle 32 will again penetrate the fabric at a position beyond the point through which the hook needle pulled the last loop. In this manner, thread will appear not as a continuous line, but, as seen on the piece 132 of fabric in Fig. 10, at alternate positions 134.

Since the apparatus is timed so that shaft 66 rotates twice for every rotation of shaft 26, tooth 94 and its associated elements will oscillate twice for every reciprocation of needles 32 and 34. However, one of those oscillations will occur when the needles are retracted from the fabric and during the forward feeding movement of the feed dogs. Thus, the tooth and its associated elements will be ineffective during that stage. By such a relationship of parts, it is possible to utilize a cam not deeply cut, and yet obtain a rapid action of tooth 94 and finger 118 so that they are effective in their respective oscillations in the very small time interval in which loop 126 is being formed and during which the thread tension is released as the needles are being retracted but still remain positioned beneath the fabric. Then the hook needle draws through the fabric the loop from the slack thread at the threaded needle, brings that loop to the outside face of the fabric, and extends the loop as the fabric is fed so that needle 32, when it again moves downwardly, will engage within the loop which becomes released from hook 128 thereafter as the hook needle enters the fabric, and pushes the loop off the hook. It is the repetition of these steps which, of course, produce the saddle stitch.

It is to be noted that, in timing the apparatus, it is possible to set tooth 94 in relation to the movement of the needles by setting shaft 66 with relation to shaft 26 through gears 70, one of the gears being conveniently supplied with a set-screw 136 or similar releasable securing means for that purpose, or in any other manner, as, for instance, by setting section 74 on shaft 66 through a suitable set-screw or similar means. As soon as the position of tooth 94 for proper cooperation with the needles has thus been determined, the setting of finger 118 can be effected by adjusting crank arm 108 on spindle 110. For this purpose, a clevis 140 contracted by a suitable screw is formed on the part of arm 108 engaging the spindle. In this manner, the two operating parts which must function in correctly timed relation to the needles may be set easily. The oscillations of tooth and finger are produced by a single cam action, that is, the engagement of pin 76 in slot 80.

In Figs. 11 and 12, a modification of the stitch-forming mechanism has been shown. In this modification, only needles 142 and 144 are shown relatively to a base 146. These parts are substantially identical with needles 32 and 34 and base 12. Likewise, a shaft 148 is carried in suitable bearings beneath base 146, and is similar in its structure and arrangement to shaft 66. Shaft 148 extends beyond a foot 150 in which the shaft is provided a bearing, and has a pin 152 provided on its end 154. This pin, like pin 76, en-

gages in slot 156 in an arm 158 which carries a plate 160 upon which is provided a loop-engaging hook 162.

Between foot 150 and arm 158, a cam 164 is carried on shaft 148. This cam may be affixed to shaft 148 in any desired manner, as, for instance, by means of a set-screw 166 which extends through the cam and engages the shaft. Of course, it is to be understood that, by this arrangement, cam 164 may be set or timed with relation to shaft 148 in determining certain of the operations of the apparatus.

Arm 158 is carried upon a stud 168 which is fixed in foot 150, a collar 170 retaining the arm in position upon the stud. The arm is oscillated by direct engagement of pin 152 in slot 156, and, by properly adjusting arm 158 with relation to shaft 148, tooth or hook 162 will be in timed relation to move past needles 142 and 144 for stretching a loop of thread from needle 142 past needle 144.

In a bracket arm 172 carried from base 146, a stud 174 is anchored by suitable means such as clevis 176. On this stud is pivotally mounted 25 a rocker arm 178 which extends upwardly towards the base and the needle plate. A roller 180 carried upon a pin 182 intermediately positioned on arm 178 is engaged within a groove 184 circumferentially formed in cam 164. From the uppermost portion of arm 178 extends a post 186 in which is fixed a pin or finger 188 having a point 190 and a vertical edge 192.

As shaft 148 rotates and oscillates hook 162, finger 188 will also be oscillated by engagement 35 of pin 182 and its roller within groove 184. Finger 188 will thus be presented between needles 142 and 144 and in engagement with the loop stretched by hook 162 from needle 142 to needle 144. The effect of this engagement of finger 40 188 with the loop will be substantially identical with the effect of the engagement of finger 118 with loop 126.

Many other changes could be effected in the 45 particular apparatus designed, and in methods of operation and use set forth, and in specific details thereof, without substantially departing from the invention intended to be defined in the claims, the specific description being merely of 50 exemplifying embodiments in accordance with the statutes.

What is claimed as new and useful is:

1. In combination, in a sewing machine, a base, a head extending from the base, a needle plate associated with the base, needles movable relatively to the head to cooperate with the needle plate, a drive in the head for the needles, a hook to engage a loop upon one needle and draw it in the direction of the other needle, a pusher for forcing the loop against the other needle, a shaft carried by the base and continuously rotated by said drive, a cam on one end of the shaft, a crank carried by said shaft end for moving the hook into loop-engaging relation, and means actuated by the cam for moving the pusher into loop-forcing relation.

2. In combination, in a sewing machine, a needle plate for supporting fabric in position to be stitched, a threaded needle and a hook needle movable together for projection through fabric supported upon the needle plate, means for moving the needles to project them through and to withdraw them from the supported fabric, a member mounted to vibrate substantially in a plane immediately contiguous and parallel to a plane including the threaded needle and the

hook needle for engaging a thread loop on the projected threaded needle and drawing it over and upon the hook of the hook needle, and a continuously rotating shaft for vibrating the member, the shaft extending substantially up to and perpendicularly to the plane of vibration.

3. In combination, in a sewing machine, a needle plate for supporting fabric in position to be stitched, a threaded needle and a hook needle movable together for projection through fabric supported upon the needle plate, means for moving the needles to project them through and to withdraw them from the supported fabric, a pivoted arm having a loop-engaging hook thereon, the arm being mounted for vibration to move the hook substantially in a plane immediately contiguous and parallel to a plane including the threaded needle and the hook needle for engaging a thread loop on the projected threaded needle and drawing it over and upon the hook of the hook needle, and a continuously rotating shaft directly engaging the arm for vibrating the loop-engaging hook from the threaded needle to the hook needle.

4. In combination, in a sewing machine, a needle plate for supporting fabric in position to be stitched, a threaded needle and a hook needle movable together for projection through fabric supported upon the needle plate, means for moving the needles to project them through and to withdraw them from the supported fabric, a continuously rotated shaft, a pivoted arm positioned to extend into immediate adjacency to the end of the shaft, interengaging means between the shaft end and the arm for converting the continuous rotation of the shaft into oscillating motion of the arm, the arm having a loop-engaging hook and being positioned in immediate adjacency to the path of movement of the needles, a loop pusher mounted to cooperate with the hook and the needles, and means for converting the rotational movement of the shaft into oscillating movement of the loop pusher.

5. In combination, in a sewing machine, a needle plate for supporting fabric in position to be stitched, a threaded needle and a hook needle movable together for projection through fabric supported upon the needle plate, means for moving the needles to project them through and to withdraw them from the supported fabric, a continuously rotated shaft, a pivoted arm positioned to extend into immediate adjacency to the end of the shaft, interengaging means between the shaft end and the arm for converting the continuous rotation of the shaft into oscillating motion of the arm, the arm having a loop-engaging hook and being positioned in immediate adjacency to the path of movement of the needles, a loop pusher mounted to cooperate with the hook and the needles, and means including the arm for converting the rotational movement of the shaft into oscillating movement of the loop pusher.

6. In combination, in a sewing machine, a needle plate for supporting fabric in position to be stitched, a threaded needle and a hook needle movable together for projection through fabric supported upon the needle plate, means for moving the needles to project them through and to withdraw them from the supported fabric, a continuously rotated shaft, a pivoted arm positioned to extend into immediate adjacency to the end of the shaft, interengaging means between the shaft end and the arm for converting the continuous rotation of the shaft into oscillating motion

of the arm, the arm having a loop-engaging hook and being positioned in immediate adjacency to the path of movement of the needles, a loop pusher mounted to oscillate between the needles, and means for converting the rotational movement of the shaft into oscillating movement of the loop pusher.

7. In combination, in a sewing machine, a needle plate for supporting fabric in position to be stitched, a threaded needle and a hook needle movable together for projection through fabric supported upon the needle plate, means for moving the needles to project them through and to withdraw them from the supported fabric, a continuously rotated shaft, a pivoted arm positioned to extend into immediate adjacency to the end of the shaft, interengaging means between the shaft end and the arm for converting the continuous rotation of the shaft into oscillating motion of the arm, the arm having a loop-engaging hook and being positioned in immediate adjacency to the path of movement of the needles, a loop pusher pivoted for movement transversely of the arm and in position to cooperate with the hook and the needles, and means including the arm for converting the rotational movement of the shaft into oscillating movement of the loop pusher.

8. A sewing machine for producing a chain stitch comprising a base, a head extending over the base, a needle bar mounted for movement in the head and towards and away from the base, feeding means in the base to feed fabric to be stitched, a threaded needle and a hook needle carried by the needle bar, a continuously rotated shaft in the head for imparting reciprocating movement to the needle bar and for driving the feeding means, a needle plate on the base for supporting fabric to be stitched, a continuously rotated shaft mounted beneath the base, an oscillating hook mounted beneath the base, a pusher mounted beneath the base, and means driven by the shaft beneath the base for imparting oscillating motion to the hook and pusher for stretching a loop from the threaded needle to the hook needle.

9. A sewing machine for producing a chain stitch comprising a base, a head extending over the base, a needle bar mounted for movement in the head and towards and away from the base, feeding means in the base to feed fabric to be stitched, a threaded needle and a hook needle carried by the needle bar, a continuously rotated shaft in the head for imparting reciprocating movement to the needle bar and for driving the feeding means, a needle plate on the base for supporting fabric to be stitched, a continuously rotated shaft mounted beneath the base driven from the continuously rotated shaft in the head, an oscillating hook mounted beneath the base, a pusher mounted beneath the base, and means driven by the shaft beneath the base for imparting oscillating motion to the hook and pusher for stretching a loop from the threaded needle to the hook needle.

10. A sewing machine for producing a chain stitch comprising a base, a head extending over the base, a needle bar mounted for movement in the head and towards and away from the base, feeding means in the base to feed fabric to be stitched, a threaded needle and a hook needle carried by the needle bar, a continuously rotated shaft in the head for imparting reciprocating movement to the needle bar and for driving the feeding means, a needle plate on the base for supporting fabric to be stitched, a continuously rotated

tated shaft mounted beneath the base driven from and at twice the speed of the continuously rotated shaft in the head, an oscillating hook mounted beneath the base, a pusher mounted beneath the base, and means driven by the shaft beneath the base for imparting oscillating motion to the hook and pusher for stretching a loop from the threaded needle to the hook needle.

11. A sewing machine for producing a chain stitch comprising a base, a head extending over the base, a needle bar mounted for movement in the head and towards and away from the base, feeding means in the base to feed fabric to be stitched, a threaded needle and a hook needle carried by the needle bar, a continuously rotated shaft in the head for imparting reciprocating movement to the needle bar and for driving the feeding means, a needle plate on the base for supporting fabric to be stitched, a continuously rotated shaft mounted beneath the base driven from and substantially parallel to the continuously rotated shaft in the head, an oscillating hook mounted beneath the base, a pusher mounted beneath the base, and means driven by the shaft beneath the base for imparting oscillating motion to the hook and pusher for stretching a loop from the threaded needle to the hook needle.

12. A sewing machine for producing a chain stitch comprising a base, a head extending over the base, a needle bar mounted for movement in the head and towards and away from the base, feeding means in the base to feed fabric to be stitched, a threaded needle and a hook needle carried by the needle bar, a continuously rotated shaft in the head for imparting reciprocating movement to the needle bar and for driving the feeding means, a needle plate on the base for supporting fabric to be stitched, a continuously rotated shaft mounted beneath the base substantially parallel to the continuously rotated shaft in the head, an oscillating hook mounted beneath the base, a pusher mounted beneath the base, and means driven by the shaft beneath the base for imparting oscillating motion to the hook and pusher for stretching a loop from the threaded needle to the hook needle.

13. A sewing machine for producing chain stitching comprising a needle bar, a needle plate, the needle bar having a thread-bearing needle and a hook, the needle bar being reciprocable to pass the needle and the hook back and forth through the needle plate, an arm beneath the plate, a pivot for the arm, the pivot and the arm being located so that the arm may oscillate in a plane immediately adjacent the plane of movement of the needle and the hook, a continuously rotating shaft extending transversely of the plane of oscillation of the arm, the shaft terminating so that its end is substantially in contact with the arm but permits the arm to oscillate across the plane of the end of the shaft, and cooperative means in the shaft and the arm for converting the rotational motion of the shaft into oscillating motion of the arm, the arm having a loop engaging means for stretching a loop from the needle onto the hook.

14. A sewing machine for producing chain stitching comprising a needle bar, a needle plate, the needle bar having a thread-bearing needle and a hook, the needle bar being reciprocable to pass the needle and the hook back and forth through the needle plate, an arm beneath the plate, a pivot for the arm, the pivot and the arm being located so that the arm may oscillate in

a plane immediately adjacent the plane of movement of needle and hook, a continuously rotating horizontal shaft extending transversely of the plane of oscillation of the arm, the shaft terminating so that its end is substantially in contact with the arm but permits the arm to oscillate across the end of the shaft, means associated with the shaft and the arm for converting the rotational motion of the shaft into oscillating motion of the arm, the arm having a loop engaging means for stretching a loop from the needle onto the hook, a vertical shaft, means actuated by the vertical shaft for pressing a stretched loop onto the hook, and means associated with said arm and said vertical shaft for converting the rotational movement of the horizontal shaft into oscillating movement of the pressing means.

15. A sewing machine for producing chain stitching comprising a needle bar, a needle plate, the needle bar having a thread-bearing needle and a hook, the needle bar being reciprocable to pass the needle and the hook back and forth through the needle plate, an arm beneath the plate, a pivot for the arm, the pivot and the arm being located so that the arm may oscillate in a plane immediately adjacent the plane of movement of needle and hook, a continuously rotating shaft extending transversely of the plane of oscillation of the arm, the shaft terminating so that its end is substantially in contact with the arm but permits the arm to oscillate across the plane of the end of the shaft, means associated with the shaft and the arm for converting the rotational motion of the shaft into oscillating motion of the arm, the arm having a loop engaging means for stretching a loop from the needle onto the hook, a cam immediately at the end of the shaft, and a rocker arm, the rocker arm carrying means for pressing a stretched loop onto the hook, the rocker arm having means to cooperate with the cam for converting the rotational movement of the shaft into oscillating loop-pressing movement of the rocker arm.

16. A sewing machine having a base, a head carried by the base, fabric supporting and feeding means carried by and associated with the base, needles movable relatively to the head for cooperation with the supporting means, a presser foot carried by the head and movable relatively to the head to engage against fabric positioned upon the fabric-supporting means, means carried by the head for moving the needles towards, away from and through fabric retained by the presser foot upon the fabric-supporting means, and means carried beneath the fabric-supporting means for cooperation with the needles in forming stitches in fabric supported and fed relatively to the base, said cooperating means including an oscillating hook and an oscillating pusher for engaging thread upon a needle and stretching it into engagement with the other needle, and means including a continuously rotating shaft beneath the base for imparting an arcuate oscillation to the hook past the needles, the movement of the needles and the cooperating means with relation to each other and to fabric upon the fabric-supporting means being independent of the position of the presser foot with relation to the fabric-supporting means.

17. In combination, in a sewing machine, a base, a head extending from the base, a needle plate associated with the base, needles movable relatively to the head to cooperate with the needle plate, a presser foot carried by and mov-

able relatively to the base for cooperating with the needle plate to retain fabric thereon, a drive in the head for the needles, a hook to engage a loop upon one needle and draw it in the direction of the other needle, a pusher for forcing the loop against the other needle, a shaft carried by the base and continuously rotated by said drive, means carried by the shaft for moving the hook into loop-engaging relation and for moving the pusher into loop-forcing relation, the movement of the needles relative to the needle plate and the movement of the hook and pusher relative to the needles being entirely independent of the position of the presser foot with relation to the needle plate.

18. In combination, in a sewing machine, a needle plate for supporting fabric in position to be stitched, means for retaining fabric to be

stitched in position for the stitching operation, a threaded needle and a hook needle movable together for projection through fabric supported upon the needle plate, means for moving the needles to project them through and to withdraw them from the supported fabric, a vibrating member for engaging a thread loop on the projected threaded needle and drawing it over and upon the hook of the hook needle, and a continuously rotating shaft for vibrating the member, the movement of the needles relative to the needle plate and of the means for moving the needles to project them through the supported fabric and the relation of the needles to the vibrating member being wholly independent of the means for retaining fabric in position for the stitching operation.

JOSEPH SCHIFTER.
